BAG CHUTE FOR HARVESTER THRESHERS

Albert B. Welty, Moline, Ill., assignor to International Harvester Company, a corporation of New Jersey

Application June 29, 1934, Serial No. 733,004

16 Claims. (Cl. 56—122)

The invention relates to improvements in bag chutes used in connection with harvester threshers.

Certain types of harvester threshers utilize a bagging platform where the threshed grain is discharged into bags held by a bag holder. When a bag is filled, an operator on the platform removes the bag from the holder and sews the open end of the bag closed. Thereupon the bag 10 of grain is deposited upon the upper end of an inclined bag chute hung from the stubbleward side of the harvester thresher. The bag thereupon slides down the chute by gravity to the lower end thereof where it is held on the chute 15 by a tail board. A number of bags can be accumulated on the chute and may be discharged from the chute together at the will of the operator, who manipulates a pull rope to release the tail board for that purpose.

20 The first bag in each accumulation of bags slides the full length of the chute and, as such filled bags are quite heavy, they hit the tail board with considerable force. This is especially true when the machine is traveling a ground 25 slope that increases the normal inclination of the bag chute. Frequently, as the result of such shock, the bags are split open and the grain therein is spilled and wasted. It is desirable, therefore, that some means be provided to overcome this difficulty.

20 The main object of the invention accordingly is to provide a bag chute having cushion means to absorb the shock of a bag striking the tail board to prevent damage to both the bag and the chute structure.

35 Another object is to provide such shock absorbing, or minimizing means, which will be simple and fool-proof in operation.

Still another object is to provide such means 40 which functions automatically.

Other objects will be apparent to those skilled 45 in this art as the disclosure is more fully made.

Briefly, such objects may be attained by the 50 illustrative structure herein disclosed in which a bag chute having a tail board is mounted for bodily shifting movement against the resistance of one or more cushion, or recoil, springs, as shown in the accompanying sheets of drawings, wherein:

55 Figure 1 is a general perspective view, looking from the front, showing the improved bag chute mounted on the stubbleward side of a hill-side or leveling type of harvester thresher;

Figure 2 is a side elevational view of the harvester thresher and bag chute; and,

Figure 3 is a detail, central, side sectional view through the upper end of the bag chute.

A harvester thresher of the hill-side type is shown, having a body 10 carrying a bagger's platform 11 and a seat 12, there being an elevator 13 for directing threshed grain from the body to a spout 14, beneath which is a bag holder 15 and a bag 16.

The front end of the machine is carried on the usual steering wheel truck 17, while underneath 10 the body is a transverse axle 18 for mounting a wheel on the grainward side of the machine, not shown. The stubbleward end of this axle carries a longitudinally rearwardly extending pivoted crank arm 19 having its rear end bent transversely for mounting a leveling wheel 20 in any usual manner. The improved bag chute will next be described.

Adjacent the platform 11 the body 10 carries a transverse, outwardly extending stationary shaft 20 or support 21, to which is connected a pair of spaced flat bars 22 that are inclined rearwardly and downwardly. The shaft 21 is suitably braced by braces 23, 24. The bag chute per se comprises an inclined board 25 embraced at its upper end by a U-shaped strap 26 and a similar strap 27 farther down. Between these straps is a third strap 28 having slots 29 through which the bars 22 slidably pass. The straps 26, 27 and 28 carry side boards 30 for the chute 25. The bars 22 thus carry the upper end of the chute from the stationary shaft 21. Springs 31 are connected to the lower ends of the bars 22, said springs being respectively connected to eyebolts 32 adjustably secured in the strap 27, as shown. By 35 means of these bolts 32, the tension of the springs can be changed as desired.

The cap 33 for the outer end of the hub of the wheel 20 carries a forwardly extending arm 34 having a right angularly and outwardly bent end 40 35, on which is carried a guide roller 36. The lower end of the chute board 25 has its under side provided with guides 37, that serve slidingly to carry the lower end of said chute on the roller 36. 45

By means of a hinge 38, a tail board, or gate, 39 is provided to close the lower end of the chute 25, said tail board having connected to it a forwardly and upwardly extending rod 40, which at its upper end is bent inwardly to form a crank 50 portion 41. The ends of said crank portion 41 are carried in the right angle slots 42 formed in guide brackets 43 mounted under the chute 25 at its side edges. The crank 41 is normally pulled by a spring 44 to hold the same up in the ver- 55

tical portion of the slot 42, thus holding the tail board 39 in chute closing position by means of the rod 40, as shown.

A rockshaft 45 is carried under the chute, said shaft having a cam 46 at one end, and a crank arm 47 at its other end. A rope 48 accessible to the operator on his station 11 is connected to the crank 47. When the rope is pulled, the cam 46 pushes the crank 47 down in the slot 42 and the weight of accumulated bags on the chute then releases the tail gate 39 to dump the bags on the ground. As soon as all bags have been thus discharged, the spring 44 is operative to restore the gate 39 and crank 47 to normal bag holding position. The parts 49 are runners to save the chute from damage, should the lower end thereof engage the ground.

From this disclosure it will now be seen that the entire bag chute structure is bodily slideable 20 on the roller 36 and that its weight is resiliently hung from the fixed bars 21 by the recoil springs 31. Consequently, when the bagger on his platform 11 drops a filled bag of grain on the upper end of the chute 25, it slides down the same by 25 gravity and hits the tail board 39 with considerable force. This force is instantly transformed into a pull that will shift the entire chute structure downwardly against the resistance of the springs 31. It is thus clear that this shock is 30 absorbed to save the bag from damage. A number of bags are accumulated on the chute and the operator discharges them when he sees fit to do so by pulling the rope 48 to release the tail gate 39, as has already been described.

35 Thus, an improved bag chute for harvester threshers and the like has been provided to attain the desirable objects heretofore recited.

It is the intention to cover all changes and modifications not departing from the scope of the 40 invention as indicated by the appended claims.

What is claimed is:

1. In a machine of the class described, the combination of an inclined chute, supporting means therefor, and means for carrying said chute on the supporting means for bodily shifting movement.

50 2. In a machine of the class described, the combination of an inclined bag chute having a tail board, supporting means therefor, and means for carrying said chute on the supporting means for bodily shifting movement when a bag slides down the chute and strikes the tail board.

55 3. In a machine of the class described, the combination of an inclined chute, supporting means therefor, and means including a resilient connection for carrying said chute on the supporting means for bodily shifting yielding movement.

4. In a machine of the class described, the 60 combination of an inclined bag chute having a tail board, supporting means therefor, and means including a resilient connection for carrying said chute on the supporting means for bodily shifting yielding movement when a bag slides down the chute and strikes the tail board.

5. In a machine of the class described, the 70 combination of an inclined bag chute, supporting means therefor, means for carrying said chute on the supporting means for bodily shifting movement, and means to guide the chute in its movement.

6. In a machine of the class described, the 75 combination of an inclined bag chute having a tail board, supporting means therefor, means including a resilient connection for carrying said

chute on the supporting means for bodily shifting yielding movement when a bag slides down the chute and strikes the tail board, and means to guide the chute in its movement.

7. The combination with a harvester thresher 5 of an inclined bag chute having a tail board, roller means to support the lower end of the chute from the harvester thresher, and resilient means to support the upper end of the chute from the harvester thresher, said chute being bodily shift- 10 able when a bag slides down the same and strikes the tail board.

8. The combination with a harvester thresher of an inclined bag chute carried thereby, and recoil means whereby the chute may shift bodily 15 when a bag slides down the same.

9. The combination with a harvester thresher of an inclined bag chute carried thereby, and spring recoil means whereby the chute may shift bodily when a bag slides down the same. 20

10. The combination with a harvester thresher of an inclined bag chute having a tail board carried thereby, and means to cushion the shock of a bag sliding down the chute and when it strikes 25 said tail board.

11. The combination with a harvester thresher of an inclined bag chute having a tail board carried thereby, and spring means to cushion the shock of a bag sliding down the chute and when it strikes the tail board. 30

12. The combination with a harvester thresher of a support extending therefrom, an inclined bar carried by the support, a spring connected to the bar, an inclined bag chute hung at its upper end from the spring, means to support the lower end of the chute from the harvester thresher, and a cross member under the chute through which said bar is slidably passed. 35

13. The combination with a harvester thresher having a longitudinal thresher part, of an upper support extending transversely therefrom, a lower support also extending transversely from said thresher part, an inclined bag chute slidably carried on said supports, and means yieldingly connecting the chute to the upper support. 45

14. The combination with a harvester thresher having a longitudinal thresher part, of an upper support extending transversely therefrom, a lower support also extending transversely from said thresher part, an inclined bag chute slidably carried on said supports, a pair of inclined bars connected to the upper shaft and extending under the bag chute, a pair of spaced cross members forming part of the bag chute, one of said cross members having a yielding connection with the inclined bars, and the other cross member having means cooperable with the inclined bars to guide the upper end of the chute in its sliding movement. 50

15. The combination with a harvester thresher 60 having a longitudinal thresher part, of an upper support extending transversely therefrom, a lower support also extending transversely from said thresher part, an inclined bag chute slidably carried on said supports, means yieldingly hanging the chute from said upper support, and means associated with each support to guide the chute in its sliding movements. 65

16. The combination with a harvester thresher, of supports extending laterally therefrom, an inclined bag chute slidably carried on the supports, and cushion means whereby the chute may have bodily shifting movement in the direction of a bag sliding down the same. 70
